United States Patent Office.

EDWARD W. BRETELL, OF ELIZABETH, NEW JERSEY.

Letters Patent No. 105,900, dated August 2, 1870.

IMPROVEMENT IN ATTACHING CAPS TO BASES OF BELL-LEVERS.

The Schedule referred to in these Letters Patent and making part of the same

I, EDWARD W. BRETELL, of the city of Elizabeth, in the State of New Jersey, have made an Improvement in the Caps used for Levers for House-Bells, of which the following is a specification.

My improvement relates to the manner of securing or attaching the cap to the base of the lever.

Hitherto, the invariable manner of attachment has been to have the bolt, shown by *a* in the drawing, riveted to the base *b*, and the nut in the cap *c*, as in Figure 5.

In my improvement the cap is perforated, and a bolt with an ornamental head inserted, with a thread on its end that screws into the end of the base *b*, as in fig 4.

In Figure 1 is shown a square hole through the cap, and in

Figure 2, the bolt through the same. In Figure 3 is a round hole, and in Figure 4 is the bolt in the hole through the cap *c*, with the end of the bolt screwed into the base *b*.

What I claim, and desire to secure by Letters Patent of the United States, is—

The combination of the base *b*, the crank-lever and perforated porcelain cap, when the three are secured together by the bolt *a*, which passes through the two latter, and is secured in the base-plate, all as and for the purpose set forth.

E. W. BRETELL.
